UNITED STATES PATENT OFFICE.

ALBERT BALL, OF CLAREMONT, NEW HAMPSHIRE, ASSIGNOR, BY MESNE ASSIGNMENTS, TO SULLIVAN MACHINERY COMPANY, OF BOSTON, MASSACHUSETTS, A CORPORATION OF MASSACHUSETTS.

STONEWORKING MACHINE.

Application filed June 1, 1912, Serial No. 701,001. Renewed March 14, 1921. Serial No. 452,226.

To all whom it may concern:

Be it known that I, ALBERT BALL, a citizen of the United States, and a resident of Claremont, in the county of Sullivan and State of New Hampshire, have invented an Improvement in Stoneworking Machines, of which the following description, in connection with the accompanying drawings, is a specification, like characters on the drawings 10 representing like parts.

My invention relates to stone working machines, being more particularly though not exclusively concerned with power driven channelers, or the like. My invention will 15 be best understood by reference to the following specification, when taken in connection with the accompanying illustration of one specific embodiment thereof, while its scope will be more particularly pointed out 20 in the appended claims:—

In the drawings:

Fig. 1 is a front elevation partly broken away of a channelling machine embodying my invention;

Fig. 2 is a plan section on an enlarged scale on line 2—2 of Fig. 1;

Fig. 3 is a plan section on an enlarged scale on line 3—3 of Fig. 1;

Fig. 4 is an end elevation of the machine 30 partly in vertical section;

Fig. 5 is a detail vertical sectional view on an enlarged scale of the frictional driving device;

Fig. 6 is a vertical sectional view partly 35 in elevation on an enlarged scale on line 6—6 of Fig. 1;

Fig. 7 is a detail sectional view partly in elevation, on the irregular line 7—7 of Fig. 6;

Fig. 8 is a plan view of the mechanism 40 partly in horizontal section, with certain parts removed; and

Fig. 9 is a detail in side elevation, showing one of the controlling levers.

My invention contemplates the provision 45 of tool actuating mechanism for a direct connected tool, such for example as the cutting tool of a channeling machine, or the like, whereby the driving motor may be mounted in convenient proximity to the tool, and so connected thereto as to actuate the tool in its reciprocatory movement to and from the work through the interven-

tion of a suitable associated elastic medium, such as compressed air.

Referring more particularly to the drawings and to the embodiment of my invention which I have there shown for illustrative purposes, I have shown my invention as applied to a standard form of channeling machine, having a base or main frame 10, which may be of any suitable type or construction, having axles 11, having thereon truck wheels 12 whereby the machine may be moved on the bottom of the 65 quarry along the usual tracks consisting of rails 13 for that purpose. Suitably mounted on the base 10 in suitable brackets thereon is a trunnion bar or shaft 14, whereon is pivoted in any suitable manner an upright standard 15, the same consisting of 70 upright supporting and guiding members united at the bottom and at the top joined by arch pieces or yokes 16. The standard may be positioned at any desired point 75 lengthwise of the machine upon the trunnion shaft 14, and may be tilted to any desired angle in any suitable manner, as by the use of adjustable braces 17, pivotally connected at their upper ends to the standard and at their lower ends to a bar or shaft 18 mounted on the base 10 at the back of the machine.

In the particular embodiment shown, the truck is propelled along the trackway under its own power, motive means therefor being herein embodied in a truck driving motor 19, herein an electric motor mounted on the base 10. For driving the truck, power is transmitted from an armature shaft 20 of the motor, through a pinion 21, secured to the latter and meshing with a gear 22, secured to a transverse transmission shaft 23, and a longitudinal driving shaft 24 near the opposite side of the truck by suitable 90 power transmitting mechanism, which will be more fully described. The driving-shaft 24 is mounted in bearings 25, upon the base, and is provided at each end with worms 26 meshing with underlying worm gears 27, the latter fixedly secured each upon one of the axles 11, the latter acting to drive the truck wheels 12 secured to the ends thereof.

As is usual in this class of apparatus, the cutting appliances are shown as mounted at 105 the front or active side of the truck, and

comprise a tool or gang of tools 28, secured to a cross-head 29, carried by a piston-rod 30. For the guidance of the cross-head, there is provided a sliding cross-head guide 31, having supplemental guides 32 secured thereto.

For the guidance of the cross-head guide, the standard is provided with guideways 33, to receive the sides of the cross-head 31 guide, and a guideway 34 to receive the back, there being provided gibbs 35 suitably to hold the cross-head guide in said guideways, (see Fig. 3).

Mounted for adjustment upon the standard 15 and toward and from the work is a sliding frame 36, to the bottom of which the sliding guide for the cross-head is bolted. As indicated more clearly in Fig. 2, the standard is finished at the front, back and inner faces, 20 to provide front guideways 37 and rear guide-ways 38, and inner guideways 39, 40 and 41. The sliding frame 36 extends entirely through the standard and locks around the back of the latter, where it is 25 provided with wearing gibbs 42, extending the whole length of the sliding frame. There are also provided wearing gibbs 43 at the front of the machine, and gib-screws 44 bearing against the latter to take up the 30 wear in the sliding frame.

The sliding frame may be raised and lowered on the standard toward and away from the work by any suitable mechanism, herein being provided for this purpose with 35 a nut 45, receiving therein a feed-screw 46, which latter is journaled in a suitable bearing 47 on the standard. This feed-screw is rotated by suitable means, providing for an angular adjustment of the standard and 40 parts carried thereby without disturbing the driving connection with the feed-screw. To this end, I preferably provide a beveled gear 48, secured to the feed-screw 46 below the bearing 47, and meshing with a beveled 45 gear 49, suitably journaled on the base 10 concentric with the pivotal axis of the standard and preferably journaled on the trunnion shaft 14. A thrust collar 50 may be provided above the bearing 47, to receive 50 the longitudinal thrust of the feed-screw in the one direction, while the hub of the gear 48 receives the thrust in the opposite direction. Power may be applied to the gear 49 from the truck driving motor by suitable 55 connections hereinafter described.

It will be observed that the location of the feed-screw below the sliding frame, where it has operative engagement at its upper end with the sliding frame and at its 60 lower end directly with the tool feeding mechanism on the truck, not only provides a very inconspicuous and compact arrangement of tool feeding parts, but leaves the upper portion of the sliding frame and the 65 standard free for the disposition of the

motor driven tool reciprocating mechanism.

In order to provide for an elastic yielding medium between the tool and its driving motor, any suitable arrangement of parts may be provided, but I have herein shown means whereby a yielding cushion of air is interposed and herein through the provision of a cooperating cylinder and piston, one of which is adapted to be connected to the tool and the other to be reciprocated by the motor. In the present instance I have shown the cross-head 29 directly connected to the piston rod 30, as hereinbefore described. The piston rod is secured to a piston 51, working in a cylinder 52, which is mounted for reciprocation in the sliding frame 36, the latter for that purpose having adjustably secured thereto suitable guides 53 (See Fig. 2), preferably provided with V-shaped guideways 54, which receive corresponding V-shaped slides 55 suitably secured to a shell 56, forming the body of the cylinder 52. The guides may be held in place by suitable gibbs 57.

While the cylinder may be of any suitable construction, it is preferably provided with cylinder heads 58 and 59, which are united by the cylinder shell 56, and preferably also united by a plurality of tie-rods 60 passing through both heads and provided with nuts 61. This construction provides for a very light, but exceedingly strong cylinder, which is also inexpensive to manufacture. Another advantage of this construction is that as the connecting rods as hereinafter described are connected to the lower cylinder head, the tie-rods are placed under tension during the working stroke when the blow is struck.

Any suitable mechanism may be employed to reciprocate the working cylinder 52, and thereby through its described connection with the tool-carrying cross-head reciprocate the latter and impart working strokes to the tool, but in the described embodiment of my invention, I have for this purpose provided the lower cylinder head 59 with wrist-pins 62 on opposite sides thereof. The lower cylinder head therefore constitutes a cross-head, to which are connected connecting rods, or pitmen, 63, pivoted on the wrist-pins 62. By placing the connecting rods on opposite sides of the cylinder, and by connecting them with the lower cylinder head, certain important advantages are gained, among them the making of a structure which is exceedingly light yet strong, owing to the fact that, as above stated, the cylinder is under tension when the blow is about to be struck. These connecting rods may receive a suitable reciprocatory movement from a crank-shaft 64 having crank pins 65, to which the connecting rods 63 are respectively connected. This crank-shaft is journaled in suitable bearings 66 and 67 on the sliding frame 36, and may receive its power

from a suitable motor 68, herein an electric motor, which may be mounted on any suitable part of the machine, but is preferably secured to the sliding frame.

- 5 The motor is provided with an armature shaft 69, which drives the crank-shaft 64 through suitable means, herein a pinion 70 secured to the armature shaft, and meshing with a gear 71 carried by the crank-shaft. 70
- 10 In the case of a mechanically actuated tool driven by a motor through transmission gearing, engagement reoccurs periodically between the same gear teeth when the maximum forces have to be transmitted and the 75
- 15 same teeth are therefore required to withstand the most excessive stresses. This results in excessive wear and the frequent breakage of the driving gears at the teeth which thus take the greatest load. In order 80
- 20 to distribute this wear throughout the different teeth of the driving gears at different times, I preferably provide means for changing from time to time the relations of the driving gears and the reciprocatory driving 85
- 25 member, so that the identity of the teeth which are in engagement at the time the maximum forces have to be transmitted will be altered from time to time and the life of the gears thereby correspondingly lengthened. For this purpose, I preferably provide between the motor and the tool-carrying element suitable means affording a slipping driving connection, permitting a slipping action to take place under resistance of 90
- 30 the working tool. While other means may be employed for this purpose, I preferably make the gear 71 in the form of a ring having an annular flange 72 interposed between a friction disk 73 secured to the crank shaft 95
- 35 64 and a friction disk 74. Suitable friction rings 75 and 76, herein made of leather, may be interposed between the flange 72 and the friction disks 73 and 74. The friction disks 73 and 74 may be urged toward each other to 100
- 40 press the friction rings 75 and 76 against the flange 72 by any suitable means, but I preferably provide for that purpose a plurality of springs 77 located in recesses 78 provided in the friction disk 74, and encircling bolts 79 provided with nuts 80. By 105
- 45 this means, the resistance afforded by the driving connection just described can be varied within wide limits. This slipping driving connection just described provides 110
- 50 for a slipping action at the moment that maximum resistance is encountered, and consequently the gear 71 is continually shifting its position around the crank shaft 64, and hence the wear upon the teeth of the gear is 115
- 55 distributed evenly around the latter. These frictional connections will be suitably adjusted to effect the desired result. 120
- 60 This construction, moreover, has the further advantage of providing for a slackening or even a complete cessation 125
- 65 of the operation of the tools, while the motor continues to run at a substantially uniform speed. Under difficult conditions of the work, while the machine is working in hard or crooked cuts, or when for any 130
- 70 other reason there is an abnormal resistance offered by the work to the tool or tool gang, the described shiftable driving connections permit a shifting, or rearrangement of the driving relationship between the motor and the tool. For example, under some circumstances, the tool gang will slow down while working in hard places, while the motor maintains a substantially constant speed. Under unusually difficult conditions of the work, the tool or tool gang may suddenly stick or stop entirely, yet without overloading the motor, or causing breakage or other damage to the motor or any other parts of the machine, the motor continuing to operate 135
- 75 at a substantially constant speed, irrespective of any slackening or cessation in the operation of the tool or tool gang due to abnormal resistance offered by the work. 140
- 80 It is apparent that since the travel of the cross-head or tool-holding means, and that of the working cylinder, is dependent on the throw of the crank-shaft, the longer the stroke the greater will be the travel of the cross-head and the heavier the blow imparted to the work. The throw of the crank shaft may be made to suit the requirements of the work to which the machine is particularly adapted. 145
- 85 The working cylinder 52 is adapted to contain both below and above the piston 51 fluid of any suitable nature, as air. It will be apparent that the elasticity of the blow depends upon the amount or degree of compression of the air or other fluid contained 150
- 90 in the working cylinder. If the fluid be under high compression, a rigid blow may be imparted to the work. By varying the degree of compression of the air, or other fluid, within the working cylinder, a more 155
- 95 or less elastic blow may be imparted, and if desired, the air compressed in the cylinder may be practically at or slightly above atmospheric pressure, in which case a very 160
- 100 elastic stroke is imparted. 165
- 105 In order to provide for the desired elasticity of the stroke, to furnish the necessary lifting and striking power, I may provide the working cylinder with a plurality of 170
- 110 ports or openings differently located longitudinally thereof. These ports may afford a free communication with the atmosphere, or may be interconnected in some manner, as by providing a conduit connecting the ports, the conduit serving as a means of communication between two portions of the cylinder. In the present instance, I have shown the working cylinder 175
- 115 52 provided with a plurality of ports 81, 82, 83, 84, 85 and 86, differently located 180

longitudinally of the cylinder, and adapted to form a means of communication between the interior of the cylinder and the atmosphere. In order that the force of the blow may be varied to suit the character of the stone or other conditions of the work, I preferably provide suitable means for closing any selected opening or openings, and to that end I have herein provided the ports 83, 84, 85 and 86 with screw-threaded plugs 87, 88, 89 and 90, respectively. It will be evident that when, during the working stroke, the piston has passed the last open port in travelling toward one end of the cylinder, the air entrapped within the cylinder will be compressed, thus forming a cushion and providing for an elastic stroke of the tool-carrying cross-head. Preferably the ports referred to are placed at opposite sides respectively of the longitudinal center of the cylinder, thus avoiding confining in the latter more air than is needed to give the desired elasticity. It will be evident that the nearer the ports are to the middle of the cylinder, the greater the amount of air that will be entrapped, and consequently, since more resistance is offered to the movement of the piston, the harder will be the blow that is struck by the tools.

If desired, I may also provide additional ports 91 and 92 in the working cylinder connected by the conduit 93. This conduit serves as a by-pass, which bypasses a certain amount of the air from one end of the cylinder to the other, as the piston travels to and fro in the latter. For example, assuming that the piston is travelling from the lower end of the cylinder to the upper end, after it passes the port 92, the air which it tends to compress in the upper end of the cylinder finds an escape from the port 91, by-pass conduit 93 and port 92, to the lower end of the cylinder, thus transferring a portion of the air from above the piston to below the latter. When, however, the piston in its upward stroke has passed beyond the port 91, the air trapped in the upper end of the cylinder will be compressed, and will give the desired elastic effect. Certain important advantages are derived from the use of this by-pass, among them the saving of power, and also the prevention of the waste of the cylinder oil, which by the use of the by-pass is thrown from one side of the cylinder past the piston to the other side of the cylinder.

Preferably the piston rod 30 has an extension 94 guided in the upper cylinder head 58, the latter for this purpose being preferably provided with a suitable bushing 95. The cylinder head 58 is preferably provided with a closed tube 96, forming a casting for the piston rod extension 94. In order to provide for a free movement of the air to and from the chamber thus formed

by the closed tube 96, the piston rod extension 94 may be provided with a passage 97 leading from said chamber to a lateral port 98, the latter adapted to communicate with the cylinder above the piston. By extending the piston rod in the described manner into the upper cylinder head, and providing a guide therefor, the piston is accurately guided and the wear is thereby greatly decreased. The placing of the connecting rods on opposite sides of the cylinder affords ample space at the upper cylinder head for providing the guide and casting so that the piston rod may be extended upwardly from the upper cylinder head as just described.

A very important advantage of the construction so far described is the improved manner in which a blow is struck and the reciprocation of the steels accomplished. Assuming the parts initially in the relative position shown in Fig. 6 and that the crank shaft is at the same time in the position corresponding to Fig. 4, it will be evident that as the crank shaft slowly begins to revolve after the motor 68 has been started, the piston 51 will be raised up, resting upon the lower cylinder head 59, to the upper limit of travel of the lower head of the cylinder. Upon the next downward movement of the cylinder the piston will tend to follow the cylinder head 59 and if the rotation is slow, gravity and friction between the walls of the cylinder and the piston will cause the piston to descend at a substantially equal rate with the cylinder, but as the speed of the rotation of the crank shaft increases, however, the cylinder, at such time as its velocity becomes greater than that produced by the combined effect of gravity and friction upon the piston, will tend to leave the piston behind, and when this difference in velocity is sufficiently great, the passage 82 and then the passage 81 will be opened to the space below the piston and the air above the piston will be considerably compressed. When this phenomenon occurs, the air above the piston will be compressed and the velocity of the piston will be rapidly increased and brought up to a point of substantial equality with that of the cylinder. It will be evident, however, that the cylinder will reverse its movement prior to the reversal of movement of the piston, for the cylinder will have passed through its point of maximum instantaneous velocity at about the time the crank pins 65 are cutting a horizontal plane passing through the axis of the crank shaft 64, whereas the piston will not reach its maximum velocity until a time somewhat later. Accordingly, as the cylinder slows down due to the phase of rotation of the crank pin 65, the piston, which reached its maximum velocity later than the cylinder, will still be traveling down-

ward at maximum velocity, in such manner as to bring the steels 28 into contact with the rock. It will be noted that as the piston moves downward relative to the cylinder, 5 the passages 81 and 82 will permit the escape of air from beneath the piston and that after both are closed, the by-pass 93 will maintain for a still longer period a substantially unretarded movement of the 10 piston relative to the cylinder. It will thus be seen that the piston having received a high velocity will strike a blow upon the rock which is measured directly by the momentum of the piston and of the connected 15 parts, and, further, that this shock will not be directly transmitted to the cylinder, but instead the piston will be picked up by the air beneath it and raised up as the cylinder rises, the cylinder having started its 20 upward travel prior to the striking of the blow, whereby the recoil of the steels from the rock synchronizes with the change in direction of travel of the cylinder. It will be understood that this effect is secured to 25 a maximum degree at a particular adjustment of the sliding frame. Further, if the steels do not come in contact with the rock, it will be evident that the piston will be cushioned by the air entrapped below it 30 after the closure of the port 92 and not strike the cylinder head.

As a means for lubricating the piston rod extension, the upper cylinder head 58 is 35 preferably provided with a lubricating chamber 99, connected by a port 100 with an annular groove 101 in the bushing 95, encircling the piston rod extension. This chamber may be filled through an upstanding filling tube 102 provided with a filling 40 cap 103. As a means for lubricating the cylinder, there may be provided a conduit 104 fixed in the cylinder head, forming a means of communication between the lubricating chamber and the interior of the cylinder. 45 Preferably this conduit is extended upwardly into the filling tube 102 to a point above the normal level of the oil, so that the latter instead of being constantly fed into the cylinder is supplied thereto gradually in 50 small quantities by slopping of the oil up and down in the filling tube.

The lower cylinder head may be provided with a suitable wearing bushing 105 for the piston rod 30, and may be provided with a 55 suitable gland or stuffing box 106, of any usual or desired construction, to prevent leakage from the cylinder around the piston rod. As a means for lubricating the piston rod 30, the lower cylinder head 59 may 60 be provided with an oil chamber 107, having a port or ports 108 communicating with smaller ports 109 provided in the bushing 105. The lubricating chamber 107 may be utilized to also lubricate the wrist pins 62, 65 the latter for this purpose being chambered

out and provided with oil holes or ports 110 leading upwardly to wearing bushings 111 provided in the connecting rods 63. The chamber 107 may be filled with lubricant through a passage 112 and filling tube 113, 70 the latter being provided with a filling cap 114. (See Fig. 7). The level of the oil will preferably be maintained slightly below the oil holes 108 and 110 so that the oil will be supplied where needed by the slopping 75 about of the oil as the cylinder is reciprocated.

Referring to the power transmission devices interposed between the engine and the truck-driving mechanism on the one hand and the tool-feeding mechanism on the other, reference may be had to Figs. 4 and 8, especially Fig. 8. From this, it will be seen that the transmission shaft 23 carries fixedly secured to its outer end a beveled gear 80 115, the latter meshing with two gear members 116 and 117, and acting to drive both of the latter at the same speed, but in opposite directions.

Both the gear, or truck driving, members 116 and 117 are mounted to rotate loosely upon a countershaft 118, but may be clutched thereto either one at will to turn the shaft in either direction, and thereby turn a pinion 119 keyed to said shaft and meshing with a gear 120, the latter being keyed to the truck driving shaft 24, hereinbefore referred to.

Any suitable form of clutching means may be employed, but since the particular character of the same is not of great consequence and is not essential to the illustration of my present invention, it will suffice to say that the gear members 116 and 117 are provided with clutches 121 and 122, respectively, operated by sliding collars 123 and 124, provided respectively with circumferential grooves 125 and 126. These grooves receive yoke-shaped arms 127 and 128, secured to a clutch-shifting slide rod 129, mounted to slide in guides 130 on the base 10. One end of this slide rod (see Fig. 9) is suitably connected to a hand lever 131, pivoted at 132 upon the frame, so that by moving the hand lever, the gear members 116 and 117 may be clutched to and unclutched from the counter shaft 118, it being understood of course that when one is clutched, the other is unclutched. Preferably the slide rod and handle are so arranged that they may be moved to any one of three positions, one of which is effective to drive the truck in one direction, another in the opposite direction, and a third, or intermediate position for securing inaction, 115 or rest.

During the operation of the machine, the channeler is advanced along the trackway, the tools acting to cut a channel groove of increasing depth. For adjustably feeding 130

the tools with their actuating faces downward upon the standard to adapt them to the increasing depth of the cut, or for elevating the tools out of the cut, the feed-screw 5 and nut hereinbefore described are employed. Referring now to the mechanism for driving the feed-screw, the gear member 49 hereinbefore referred to may be provided with a spur gear portion 133, which 10 may be placed in mesh with either of the two spur gears 134 and 135, suitably secured to a shaft 136, journaled in suitable bearings 137 and 138 on the base 10. When the standard is slid along the trunnion shaft 15 from one end of the machine to the other, the standard carries with it the beveled gear 49 and spur gear 133, and in order to avoid possible breaking of the teeth of the gears 133, 134 and 135, the two latter gears are 20 preferably secured to the shaft 136 by suitable means, as for example set screws 139 and 140, which permit these gears to be slid out of the way, and after the standard has been moved into place, either gear, as 25 the case may be, is slid back into mesh with the gear 133, and held in place by its set screw. It will now be evident that when the standard is set at one end of the machine, the gear 133 will be driven by the gear 134, and when the standard is set at 30 the other end of the machine, the gear 133 will be driven by the gear 135.

The shaft 136 may be driven in any suitable manner from the transmission gearing hereinbefore referred to, but for that purpose said shaft herein has a gear 141 secured thereto, meshing with a gear 142, the latter secured to a shaft 143, journaled in the bearings 137 and 138 hereinbefore referred to. 35 If desired, the shaft 143 may be provided with squared ends 144 and 145, to receive a suitable crank (not shown), by means of which the shaft 143 may be manually rotated to elevate and depress the sliding frame 36 when there is no power on. Secured to the shaft 143 (see Fig. 1) is a gear 146, meshing with a gear 147, the latter (see Fig. 8) being formed on or secured to a sleeve 148, the latter mounted for loose rotation on the driving shaft 24. For turning the sleeve 148 in either direction at will thereby to raise or lower the tools, the sleeve may be provided at opposite ends thereof with suitable clutch devices 149 and 40 150, which may be clutched to or unclutched from oppositely driven driving members 151 and 152 by devices generally similar to those previously described. The driving member 151 is provided with a spur gear 153, which meshes with a spur gear 154, formed on the truck driving gear member 116, while the tool feeding driving member 152 is provided with a spur gear 155, meshing with a similar gear 156, formed on the truck driving gear 117. From this it fol-

lows that the driving members 151 and 152 are constantly driven in opposite directions, so that by clutching one or the other to drive the spur gear 147 as described, the tools may be raised or lowered. 70

As in the case of the clutching devices for the truck driving member, the clutching devices 149 and 150 are adapted to be actuated by sliding sleeves 157 and 158 simultaneously shifted in either direction by 75 arms 159 and 160 attached to a shiftable actuating rod 161 adapted to be shifted by a hand lever 162, these connections being substantially similar to those of the truck driving member already described and fully 80 illustrated. By these described connections, the feed-screw may be turned in one direction or the other, or allowed to remain stationary at will. The improved feeding mechanism for tools is not claimed herein, 85 but in my copending divisional application, Serial No. 714,972, filed May 21, 1924.

While I have shown and described one form of my invention for illustrative purposes, and have disclosed and discussed in 90 detail the construction and arrangement incidental to one specific embodiment thereof, it is to be understood that the invention is limited neither to the mere details or relative arrangement of parts, nor to its specific 95 application herein shown, but that extensive deviations from the illustrated form or embodiment of the invention may be made without departing from the principles thereof. 100

Having thus described one form of my invention, what I claim is:—

1. In a machine of the class described, the combination of a crank-shaft, a cylinder comprising two heads, a pair of connecting rods disposed on opposite sides of said cylinder, connected directly to said crank-shaft and to the further cylinder head, and a tool-actuating piston mounted to reciprocate within said cylinder. 105

2. In a machine of the class described, the combination of a crank-shaft, a cylinder comprising two heads and tie members connecting said heads, a pair of connecting rods disposed on opposite sides of said cylinder connected to said crank-shaft and directly to the further cylinder head, and a tool-actuating piston mounted to reciprocate within said cylinder. 115

3. In a machine of the class described, the combination of a crank-shaft, a cylinder, a cross-head carried by said cylinder and having a wrist-pin, a connecting rod connecting said wrist-pin to said crank-shaft, said cross-head being provided with a lubricating chamber for said wrist-pin, and a piston mounted to reciprocate within said cylinder. 125

4. In a machine of the class described, the combination of a cylinder having a 130

cylinder head and a piston mounted to reciprocate within said cylinder and having a piston rod extended beyond said cylinder head, said cylinder head being provided with a chamber for said piston rod extension, and a passage providing constant communication between said chamber and one end of the said cylinder.

5. In an apparatus of the class described, the combination with a tool, of a driving motor, a cylinder, a piston contained within the cylinder and connected to the tool, a crank shaft driven by the motor, a pair of cylinder heads, and a pair of connecting rods reciprocated by the crank shaft and disposed on opposite sides of the cylinder, said rods being connected directly to the cylinder head nearest the tool.

6. In a channeler, a driving motor, a cylinder having upper and lower heads, a piston contained within the cylinder and having oppositely extending piston rods guided by said heads, a tool carried by the piston, a crank shaft disposed above the piston, driving connections between one end of the same and said motor, and a pair of connecting rods connected to said crank shaft and directly to the lower cylinder head.

7. In a machine of the class described, the combination of a cylinder having cylinder heads, a piston within said cylinder, means for attaching a tool to said piston, and means connected directly to the cylinder head adjacent said last named means for actuating said cylinder.

8. In a machine of the class described, the combination of a cylinder having cylinder heads, said cylinder having a plurality of openings to the atmosphere differently located longitudinally of the cylinder, means for closing any selected opening, a piston within said cylinder, means for attaching a tool to said piston, and means connected directly to the cylinder head adjacent said last named means for actuating said cylinder.

9. In a machine of the class described, the combination of a cylinder having cylinder heads, said cylinder having a plurality of openings differently located longitudinally of the cylinder, means connecting said openings, a piston within said cylinder, means for attaching a tool to said piston, and means connected directly to the cylinder head adjacent said last named means for actuating said cylinder.

10. In a machine of the class described, the combination of reciprocating tool carrying means including a reciprocable cylinder having cylinder heads, driving means, and means including a slip connection for connecting said driving means directly to the cylinder head adjacent the tool.

11. In a stone working machine, in com-

bination, a cutting tool, actuating means therefor, a cylinder having cylinder heads, a piston in said cylinder, means for controlling the relative movement of said cylinder and piston and for maintaining a circulation and renewal of air in said cylinder, and driving connections between said actuating means and said cylinder including a member connected directly to the cylinder head adjacent the tool.

12. In a machine of the class described, the combination of a cylinder and a piston mounted to reciprocate within said cylinder, means for reciprocating one of said elements, a tool attached to the other of said elements, said reciprocated element being operative to give impetus to said tool carrying element, and means permitting the free movement of one of said elements with respect to the other after said tool carrying element has acquired an impetus from a position to the rear of its mid-position with respect to the other element to a position materially forward of such mid-position, said means comprising a bypass passage opening at its ends into the cylinder bore at spaced points, each of the communications of said bypass passage with the cylinder bore being opened and closed at least once in each complete relative reciprocation of said elements.

13. In a machine of the class described, the combination including a cylinder and a piston mounted to reciprocate within said cylinder, means for reciprocating one of said elements, a tool attached to the other of said elements, said reciprocated element being operative to transmit impetus to said tool carrying element, and means forming a by-pass for transmitting fluid from the chamber formed between one end of the cylinder and the piston to the chamber between the other end of the cylinder and the piston to permit the free movement of the tool carrying element with respect to said reciprocated element after said tool carrying element has acquired its impetus.

14. In a machine of the class described, the combination of a cylinder and a piston mounted to reciprocate within said cylinder, means for reciprocating one of said elements, a tool attached to the other of said elements, said reciprocated element being operative to give impetus to said tool carrying element, and means permitting the free movement of one of said elements with respect to the other after said tool carrying element has acquired the impetus and comprising a bypass passage opening at its ends into the cylinder bore at spaced points, said communications of said bypass passage with the cylinder bore being open simultaneously at the relative mid-positions of the cylinder and piston, whereby the momentum of the tool carrying element and

- the tool determines the force of the blow.
15. In a machine of the class described, the combination including a cylinder and a piston mounted to reciprocate within said cylinder, means for reciprocating one of said elements, a tool attached to the other of said elements, said reciprocated element being operative to give impetus to said tool carrying element, and a by-pass adapted
- 10 to interconnect the ends of the cylinder in certain relative positions of said cylinder and piston and operative to transmit pressure fluid from below the piston to the upper side thereof to permit the free movement of
- 15 the tool carrying element with respect to said reciprocated element after said tool carrying element has acquired its impetus, whereby the force of the blow is determined by the momentum of the tool carrying element and tool.
16. In a machine of the class described, the combination of a cylinder and a piston reciprocable within said cylinder, means for positively reciprocating one of said elements, a tool attached to the other of said elements, said reciprocated element being operative to impart impetus to said tool carrying element, means for admitting and discharging air to and from said cylinder
- 25 during relative reciprocation of said cylinder and piston, and means operative to interconnect the ends of the cylinder to bypass air from one side of said piston to the other whereby impetus may be transmitted from said positively reciprocated element to said tool carrying element and said latter element thereafter permitted to move freely relative to said reciprocated element.
17. In a machine of the class described,
- 40 the combination of a cylinder and a piston reciprocable within said cylinder, means for positively reciprocating one of said elements, a tool attached to the other of said elements, said reciprocated element being operative to impart impetus to said tool carrying element, means spaced from the ends of said cylinder for admitting and discharging air to and from said cylinder during relative reciprocation of said cylinder
- 45 and piston, and means operative to by-pass air from one side of said piston to the other, said by-passing means opening into said cylinder nearer the ends thereof than said admitting and discharging means, whereby
- 50 impetus may be transmitted from said mechanically reciprocated element to said tool carrying element and said latter element thereafter permitted to move freely relative to said reciprocated element.
- 55 18. In a machine of the class described, the combination of a cylinder and a piston reciprocable within said cylinder, means for mechanically reciprocating one of said elements, a tool attached to the other of said elements, said reciprocated element being
- 60 operative to give impetus to said tool carrying element, means whereby relative movement of said cylinder and piston may cause admission and discharge of air to and from said cylinder, and means communicating with the bore of the cylinder at points spaced longitudinally of the cylinder by a distance greater than the thickness of the piston, whereby air may be by-passed from one side of said piston to the other, whereby
- 65 after impetus has been transmitted from said reciprocated element to said tool carrying element the latter element may move freely relative to said reciprocated element.
19. In a machine of the class described, the combination of a crank shaft, a cylinder, a cross head carried by said cylinder and having a wrist-pin, a connecting rod connecting said wrist-pin to said crank shaft, a piston mounted to reciprocate in said cylinder and having a rod projecting through and guided in each end of said cylinder, lubricant chambers disposed adjacent each end of said cylinder, means for distributing lubricant therefrom to said rod, and means for distributing lubricant from one of said chambers to said wrist-pin.
20. In a machine of the class described, the combination of a crank shaft, a cylinder, a cross head carried by said cylinder and having a wrist-pin, a connecting rod connecting said wrist-pin to said crank shaft, a piston mounted to reciprocate within said cylinder and provided at opposite sides with rods extended through and guided in the ends of said cylinder, a lubricant chamber for said wrist-pin disposed in said cross head, and means carried by said cylinder to lubricate said rod extensions and piston.
21. In a machine of the class described,
- 105 the combination including a cylinder member, a piston member therein, means for positively reciprocating one of said members, a tool operatively connected to the other of said members, and means for interconnecting the spaces within the cylinder member at opposite sides of the piston member when said members are in a predetermined relative position.
22. In a machine of the class described,
- 110 the combination including a cylinder member, a piston member therein, means for positively reciprocating one of said members, a tool operatively connected to the other of said members, means for admitting fluid to the interior of said cylinder member, and means for interconnecting the spaces within the cylinder member at opposite sides of the piston member when said members are in a predetermined relative position.
23. In a machine of the class described,
- 115 the combination including a cylinder member, a piston member therein, means for positively reciprocating one of said mem-

bers, a tool operatively connected to the other of said members, means for exhausting fluid from the interior of said cylinder member, and means for interconnecting the 5 spaces within the cylinder member at opposite sides of the piston member when said members are in a predetermined relative position.

24. In a machine of the class described, 10 the combination including a cylinder member, a piston member therein, means for positively reciprocating one of said members, a tool operatively connected to the other of said members, means connecting 15 the interior of said cylinder member with the atmosphere opened and closed by said piston member during relative reciprocation of said members, and means for interconnecting the spaces within the cylinder member 20 at opposite sides of the piston member when said members are in a predetermined relative position.

25. In a machine of the class described, 25 the combination including a cylinder member, a piston member therein, means for positively reciprocating one of said members, a tool operatively connected to the other of said members, means connecting the interior of said cylinder member with the 30 atmosphere opened and closed by said piston member during relative reciprocation of said members, and means including a by-pass passage opening through the wall of said cylinder member for interconnecting the 35 spaces within the cylinder member at opposite sides of the piston member when said members are in a predetermined relative position.

26. In a machine of the class described 40 the combination including a cylinder member, a piston member therein, a tool operatively connected with one of said members, means for positively reciprocating the other of said members to cause reciprocation of said first mentioned member, and means for permitting said tool carrying member to travel freely relative to said other member for less than its full path including means for interconnecting the chambers in said cylinder member on opposite sides of said piston member.

27. In a machine of the class described, 45 the combination including a cylinder member, a piston member disposed therein, a tool operatively connected to one of said members, means for positively reciprocating the other of said members to cause the compressions of the fluid between the piston member and the ends of the cylinder member 50 which occur on relative movements of said members to cause reciprocation of said member to which a tool is operatively connected in stepped relation to said positively reciprocated member, and means including a bypass operative to intermittently in-

terconnect the spaces at the opposite sides of the piston member in order to delay substantial compression of fluid between the approaching ends of the piston and cylinder members until the member to which 50 said tool is connected is materially beyond its mid-position relative to said positively reciprocated member.

28. In a machine of the class described, 55 the combination including a cylinder member, a piston member disposed therein, a tool operatively connected to one of said members, means for positively reciprocating the other of said members to cause the compressions of the fluid between the piston 60 member and the ends of the cylinder member which occur on relative movements of said members to cause reciprocation of said member to which the tool is operatively connected in stepped relation to said positively reciprocated member, and by-pass means 65 communicating with the bore of said cylinder at points more remote from the center point thereof than one-half the thickness of the piston and operative to interconnect the 70 spaces at the opposite sides of the piston member to permit the flow of the fluid from one side of said piston member to the other to delay substantial development of throwing pressures until the piston member is materially beyond its mid-positions in said 75 cylinder member.

29. In a machine of the class described, 80 the combination including a cylinder member, a piston member disposed therein, a tool operatively connected to one of said members, means for positively reciprocating the other of said members to cause the compressions of the fluid between the piston member and the ends of the cylinder member which occur on relative movements of said members to cause reciprocation of said member to which the tool is operatively connected in stepped relation to said positively reciprocated member, separate means 85 for connecting each end of the interior of the cylinder with the atmosphere, communication between said means and an end of said cylinder being closed upon movement of the piston member substantially from 90 mid-position in said cylinder member toward that end thereof, and means for delaying material compression of the fluid between the ends of the cylinder member and the piston member until the position of said 95 piston member is materially nearer the end of said cylinder member than at the time of closure of said connecting means.

30. In a machine of the class described, 100 the combination including a cylinder member, a piston member disposed therein, a tool operatively connected to one of said members, means for positively reciprocating the other of said members to cause the compressions of the fluid between the piston 105 member and the ends of the cylinder member which occur on relative movements of said members to cause reciprocation of said member to which a tool is operatively connected in stepped relation to said positively reciprocated member, and means including a bypass operative to intermittently in-

member and the ends of the cylinder member which occur on relative movements of said members to cause reciprocation of said first mentioned member in stepped relation 5 to said second member, and means for delaying the substantial development of throwing pressures until the piston member is materially beyond its mid-position in said cylinder including bypass means communicating at points spaced further than the length of the piston with the bore of said cylinder, said points of communication being so disposed that said positively recipro-

cated member has begun its upward movement prior to the instant of impact of said 15 tool upon the rock and the lifting action of the compressed fluid between the members maintains the upward movement due to rebound of the tool from the rock.

In testimony whereof, I have signed my 20 name to this specification, in the presence of two subscribing witnesses.

ALBERT BALL.

Witnesses,

MORRIS P. HOLMES,
THOMAS OFFICER.
